UNITED STATES PATENT OFFICE.

CORTEZ W. TOWNSEND, OF CANTON, OHIO.

ROLL-POLISHER.

1,072,195.

Specification of Letters Patent.

Patented Sept. 2, 1913.

Application filed August 31, 1912. Serial No. 718,025.

To all whom it may concern:

Be it known that I, CORTEZ W. TOWNSEND, a citizen of the United States, residing at Canton, in the county of Stark and State of Ohio, have invented a new and useful Roll-Polisher, of which the following is a specification.

My invention relates to improvements in means for polishing the rolls of rolling mills and the like and more particularly to means adapted to be connected to the mill and to operate continuously and automatically so as to constantly maintain the surface of said rolls in polished condition.

The objects of the invention are to generally improve devices of the character mentioned, and to provide a neat, compact device which will be capable of being attached to a mill of ordinary construction at but slight expense and without making any changes in the mill itself.

It is a further object of the invention to provide means which will operate continuously and automatically, which may be adjusted so as to polish the rolls uniformly at all times and obviate the necessity of discontinuing rolling while the rolls are being periodically polished, as has heretofore been the custom.

These objects, together with other objects apparent to those skilled in the art, may be attained by the construction illustrated in the accompanying drawings, although the invention may be embodied in other forms, the construction illustrated being chosen by way of example.

In the drawings Figure 1 is an elevation of a rolling mill showing one of my invented roll polishers thereon. Fig. 2 is a sectional view of the same on the line 2—2 of Fig. 1. Fig. 3 is an enlarged fragmentary, vertical sectional view of the upper and lower rolls showing the application of the polishers thereto. Fig. 4 is a fragmentary, perspective view of one form of polishing blade. Fig. 5 is a transverse section of another form of polishing blade. Fig. 6 is a fragmentary elevation of a polishing blade connected to the back of a lower roll polisher.

Throughout the several views similar reference numerals indicate similar parts.

Heretofore in the practical operation of rolling mills, and more especially in the operation of sheet, tin and black-plate mills the polishing of the rolls has constituted one

of the most troublesome, vexatious and expensive problems.

The great cost of rolls and the care with which they must be made and used are fundamental facts of common knowledge to those skilled in the art. The rolls are so made as to produce the proper gage and quality of product when they are in actual, practical operation. When the rolls are cool the product is of inferior grade and uncertain gage and in order to produce rolled metal of uniformly high standard of quality it is desirable that the rolls be operated as continuously as possible so that the temperature thereof may remain substantially uniform. In use the finely polished surfaces of the rolls become scratched, abraded and roughened. The demand of the trade is for a product having a smooth and even surface and in order to maintain the rolls in proper condition to produce such metal frequent polishings have been thought necessary. This polishing has commonly been accomplished by manually holding a large polishing block of carborundum or the like against the rolls or by a somewhat crude device adapted to be temporarily clamped to the mill, whereby a rotary grinding wheel could be brought into contact with the rolls. With either of these methods, however, it has been necessary to remove a part of the attachments belonging to the mill in order to make the rolls accessible for the polishing operation and the removal of these attachments, the polishing itself, and the subsequent assembling of the attachments preparatory to rolling requires considerable time. The rolls thus become cool, the mill crew scattered and the operation necessarily results in a very considerable economic loss for all concerned. Attention should also be called to the fact that the product of mills so ground must necessarily be of unequal quality, for the product of the mill immediately after the polishing, when the surfaces of the rolls are in the best condition, is poor because the rolls are cool. By the time the rolls have been heated by further working the surfaces have already become somewhat scratched and uneven and at the time the rolls are in the best condition as to temperature the surfaces of the rolls have already lost their high polish. As the work proceeds the surface of the rolls becomes more and more scratched and uneven, and the product, although produced

110

on properly heated rolls at this period becomes poorer and poorer in quality of surface until the point is reached where the rolls must, of necessity, be repolished. It is, therefore, plainly to be seen that by the method heretofore in use the product cannot possibly be of uniform quality.

By my invention I propose to remedy the above described unsatisfactory and undesirable condition by providing a polishing device which is constantly in operation, thus maintaining the surfaces of the rolls in uniformly perfect condition at all times and obviating the necessity of discontinuing rolling for the purpose of polishing. Thus the rolls may be maintained at uniform temperature at all times by reason of their constant use and not only will the product be of uniform gage and quality of surface, but the economic loss incident to discontinuing rolling at frequent intervals will be avoided.

Referring now more specifically to the construction illustrated in the accompanying drawings the numerals 1—1 indicate the housings of a rolling mill of usual construction. The numeral 2 indicates the upper roll and the numeral 3 the lower roll of the mill which rolls may be of the plain or of the well known concave type. In connection with the housings and rolls I have also illustrated the fore plate 4 in Fig. 2 to indicate the front or roller's side of the mill. All of these parts are of common and well known construction and require no further specific description.

Essentially my invention comprises a polishing blade or member held in constant frictional contact with the surface of the roll, means being provided for properly distributing and varying such contact and for generally increasing or diminishing the force of contact as may be required.

In the drawings I have illustrated two different methods of carrying out the essential inventive principle above indicated. For the upper roll I have shown the polishing blade as held against the roll by the operation of springs, whereas for the lower roll I have shown means by which the same result may be accomplished by the use of a weight.

Referring now to the upper roll polisher, the numerals 5 indicate short pins fixedly connected to the housings of the mill and constituting studs upon which the polisher carrying brackets 6 are pivotally mounted. Each of said brackets comprises a depending arm 7, the lower end of which is pivotally connected to the pin 5, an intermediate blade-back-attaching portion 8, and a power applying arm 9 extending outwardly from the roll 2 at substantially right-angles to the axis of the pins 5.

Extending from one portion 8 to the

other is the blade back 10, same being fixedly connected to the two portions 8 in any suitable mechanical manner, such connection being preferably strengthened by a corner brace 11 comprising a short piece of angle steel or the like connected to the portion 8 and to the back 10 by rivets 12. On the side of the back 10 adjacent the roll 2 is the blade retaining flange 13 fixedly held in spaced relation with reference to the back 10 by means of rivets 14 and spacing sleeves 15. Adjacent the upper edge of the back 10 is a series of screw threaded apertures 16 in which are arranged set screws 17 for the purpose of adjusting the pressure of the polishing blade against the roll, as will hereinafter more fully appear.

The upper polishing blade is preferably of the form illustrated in Fig. 4 where it will be seen that same consists of two spaced members 18 and 19 connected at their bases to the outer strengthening strips 20 and the spacing strip 21 by means of rivets 22. Each of the members 18 and 19 are preferably composed of a number of pieces or sections abutting at their end edges as illustrated at 23. The purpose of forming the members in this manner is to provide for variation and adjustment of pressure and position to conform to the surface and shape of the roll. It should also be noted that the member 19 is of less height than the member 18 for the purpose of conforming to the curve of the roll, as shown in Fig. 3, in order that both members 18 and 19 may engage the roll. The edge of the blade provided with the strips 20 and 21 is arranged between the flange 13 and the back 10 and some means is provided for loosely attaching the blade to the back 10. This may be accomplished by means of an ordinary bolt, not shown, passing through the flange 13, aperture 24 at the base of the blade, and back 10, the aperture 24 being of greater diameter than the bolt so as to allow some looseness or play, as more fully illustrated as to the lower blade in Fig. 5. The upper blade having been attached to the back 10 as described the various set screws 17 are turned to bring the members 18 and 19 into frictional contact with the roll 2. After some use it will be understood that said members will be worn, as shown in Fig. 3, which is rather desirable as giving a better frictional contact than when the blades are new.

For the purpose of drawing upwardly upon the outer end of the arms 9 to produce proper frictional contact of the blade against the roll 2 the draw rods 25 are provided, which rods are pivotally connected at 26 to the arms 9, slidably extend through the ears 27, fixedly connected to the housings 1, and are provided at their extreme upper ends with screw threads and nuts 28.

Intermediate the nuts 28 and the ears 27 are arranged compressible coil springs 29 and it will be understood that by drawing up the nuts 28 a spring-imposed pressure may be exerted upon the polishing blade against the upper roll.

Referring now to the construction illustrated as applied to the lower roll, it will be noted that pins 5^a similar to the pins 5 are 10 fixedly connected to the housings 1. Each of the polisher-carrying brackets 6^a comprises a blade-back-attaching portion 8^a and an attaching arm 7^a, the upper end of which is pivotally connected to one of the pins 15 5^a. Extending from one portion 8^a to the other is the blade-back 10^a which is fixedly connected to the said portion 8^a in any suitable mechanical manner. Preferably intermediate the ends of the back 10^a 20 a weight arm 30 is fixedly connected thereto, as by the rivets 31, and extends outwardly from the roll 3 at substantially right-angles to the axis of the pins 5^a. A weight, 32, is slidably arranged upon said arm and a set 25 screw 32^a, for holding the weight in desired adjustment is provided.

On the side of the back 10^a adjacent the roll 3 is the blade retaining flange 13^a fixedly held in spaced relation to said back by 30 means of rivets 14^a and spacing sleeves 15^a. Adjacent the lower edge of the back 10^a is a series of screw threaded apertures 16^a in which are arranged set screws 17^a.

The lower roll polishing blade is prefer- 35 ably formed of two members, 33 and 34, arranged face to face, for increasing the flexibility of the blade. Adjacent its upper edge said blade is provided with apertures 35 through which bolts 36 extend to loosely 40 attach the blade to the flange 13^a and back 10^a, as illustrated more clearly in Fig. 5. When the lower blade has been thus attached the set screws 17^a may be turned to bring the said blade into proper frictional contact with the roll 3 and the weight 32 may 45 be adjusted upon the arm 30 to produce the force of contact necessary to properly polish the roll.

In Fig. 3 the arrows adjacent the rolls 2 and 3 indicate their respective directions of 50 rotation. It will be noted that the polishing blades are so disposed that the rolls rotate in a direction from the free edge toward the attached edge, thus at all times holding 55 the blades firmly in place between the flanges 13—13^a and backs 10—10^a respectively and enabling very delicate adjustment and distribution of pressure by means of the set screws 17 and 17^a.

60 While I prefer to use high carbon steel for making the polishing blades I do not desire to be limited as to material in this respect, and the form and construction of the blades may vary in accordance with circumstances and requirements. In the opera-

tion of the device the pressure applying means, such as the springs 29 and weight 32, should be carefully adjusted so as to impose only sufficient pressure to over-come the abrasion of the surfaces caused by rolling metal, so that the polish of said surfaces may be uniformly maintained. Care should also be exercised to properly adjust the set screws 17 and 17^a from time to time to properly distribute the polishing action of the 75 blades.

I especially desire to call attention to the fact that while I have shown both upper and lower roll polishing means located on the same side of the mill it is obvious that the 80 same would operate equally as well if located on opposite sides of the mill.

Various other changes of form and detail may be made as circumstances require or experience suggest without departing from the spirit of the invention within the scope of the appended claims.

I claim:

1. For a rolling mill, means for polishing off the substance of a roll at the rolling surface thereof to uniformly counter-act the roughening abrasion of said surface produced by rolling, said means comprising, in combination with said roll, a flexible metallic polishing member adapted to flexibly 90 conform to said surface and holding means engaging said polishing member and adapted to constantly hold said member in roll-substance-polishing contact with said surface during the operation of rolling. 100

2. For a rolling mill, means for polishing off the substance of a roll at the rolling surface thereof to uniformly counter-act the roughening abrasion of said surface produced by rolling, said means comprising a flexible metallic polishing member adapted to flexibly conform to said surface and to be constantly held in roll-substance-polishing contact with said surface during the operation of rolling. 105

3. For a rolling mill, means for polishing off the substance of a roll at the rolling surface thereof to uniformly counter-act the roughening abrasion of said surface produced by rolling, said means comprising a 115 plurality of metallic members, each composed of a plurality of flexible sections, means for holding said members in roll-substance-polishing contact with the roll during the operation of rolling, and means 120 for variously distributing and adjusting the pressure of said metallic members against said surface.

4. For a rolling mill, means for polishing off the substance of a roll at the rolling surface thereof to uniformly counter-act the roughening abrasion of said surface produced by rolling, said means comprising a 125 flexible metallic polishing member, a polishing-member-holding means, pressure exert- 130

ing means and adjusting means, said holding means connected to the housings of the mill, said polishing member held by said holding means, said pressure exerting means connected to said holding means and adapted to actuate the same to bring said polishing member into roll-substance-polishing contact with said surface, and said adjusting means connected to said holding means and adapted to engage and flex said polishing member to adjust and variously distribute the pressure of said member upon said surface.

5. For a rolling mill, means for polishing off the substance of a roll at the rolling surface thereof to uniformly counter-act the roughening abrasion of said surface produced by rolling, said means comprising brackets pivotally connected to the housings 10 of the mill, a blade back connected to said

brackets, a flexible metallic polishing blade adjustably connected to said blade back, means connected to said brackets for pivotally moving the same to throw said polishing blade into roll-substance-polishing contact with said surface and means connected to said blade back and engaging said blade for distributing the pressure of said blade back against said blade, whereby to variously adjust the polishing pressure of said 25 blade against said surface throughout the length of said blade.

15 In testimony that I claim the above, I have hereunto subscribed my name in the presence of two witnesses.

CORTEZ W. TOWNSEND.
